CLAIM

We claim the ornamental design for a lilly pad shower sprayer, as shown and described.

DESCRIPTION

FIG. 1 is a perspective view of the lilly pad shower sprayer. FIG. 2 is another perspective view of one pad of the lilly pad shower sprayer; and,

FIG. 3 is a top view of one pad of the lilly pad shower sprayer.

The broken line showing is for illustrative purposes only and forms no part of the claimed design.
